S. NICAS

RAILROAD TIE AND RAIL

Filed Nov. 14, 1923

Stephen Nicas ^{Inventor}

by F. E. Hunter

Attorney

UNITED STATES PATENT OFFICE.

STEPHEN NICAS, OF EL PASO, TEXAS.

RAILROAD TIE AND RAIL.

Application filed November 14, 1923. Serial No. 674,726.

To all whom it may concern:

Be it known that I, STEPHEN NICAS, a citizen of the United States, residing at El Paso, Texas, have invented certain new and useful Improvements in Railroad Ties and Rails; and I do hereby declare the following to be a full, clear, and exact description of the invention, such as will enable others skilled in the art to which it appertains to make and use the same.

The present invention relates to improvements in railroad ties and rails in which the use of a concrete tie is permitted while dispensing with spikes and plates for connecting the rails to the ties.

The invention aims to anchor the rail more securely to the tie and to prevent spreading of the rails or of the tendency to get out of alinement and to simplify the construction to a great extent while dispensing with the expense and trouble incident to the use of spikes, plates and the like by which the rails are secured at the present time to the wooden ties.

With the foregoing and other objects in view, the invention will be more fully described hereinafter, and will be more particularly pointed out in the claims appended hereto.

In the drawings, wherein like symbols refer to like or corresponding parts throughout the several views:

Figure 1 is a perspective view, partly in section, showing a railway constructed according to the present invention.

Figure 2 is a side view thereof, and

Figure 3 is a section through one of the rails and ties on an enlarged scale.

Referring more particularly to the drawings, 4 designates the head of a usual form of T-rails made from metal and having the web 5, but being without the usual horizontal flanges extending in opposite directions. Instead, the construction is forked at the base of the web 5 providing the divergent legs 6 and 7 which may be easily and conveniently formed by initially rolling an extended web 5 of uniform thickness and afterwards dividing the web at its lower portion and forming the divergent or diagonal legs 6 and 7, which need not be of as great thickness as the web 5. Immediately beneath the web is a shoulder 8 between the two legs 6 and 7 which will seat upon the tie 9 which is of concrete. The legs 6 and 7

are imbedded in the concrete below the upper surface thereof, and these legs do not rest upon the upper surface as in the case of the horizontal flanges. The legs 6 and 7, by reason of their divergent relation, enclose a substantially wedge shaped space which is filled with the concrete of the tie when the tie is moulded or formed about the rails. This formation takes place in situ. The wedge or block of concrete immediately beneath the web of the rail forms an effective support for the rail and prevents the sinking of the rail in the concrete mass while the shoulder 8 rests upon substantially the entire depth of the tie and is thus amply supported. The legs 6 and 7, because of their diagonal positions, prevent the distortion of the rail laterally upon the tie. The exterior surfaces of the divergent legs are opposed to a turning movement of the rail, such as rocking of the rail laterally upon the tie by the substantially right angular resistance afforded by adjacent portions of the concrete mass, while a similar force opposes a like motion of the rail upon the interior faces thereof. On any tendency to rock, the forward leg will tend to descend more deeply into the concrete due to the inclination of the face thereof and the inclination of the concrete wall opposed thereto; while the rear leg will tend to ride up the inclined face of the concrete wedge so that the two actions will be opposed and substantially equal, and the rail will be secured against any possible rocking movement and this is important in avoiding spreading of the rails.

In building the track, the rails are initially laid upon appropriate supports. These supports may be blocks of wood similar to railroad ties or the supports used for holding metallic reinforcing elements while concrete is molded about the same. These supports will generally be laid between the ties and molds will be assembled at the places where the ties are to rest. Concrete is then poured into the forms through which the lower portions of the rails project and the ties are formed in situ. The concrete is allowed to set and the supports are thereupon removed. While the concrete is still slightly green, or just before final setting thereof, it is preferable to remove the supports in order to allow the weight of the rails to devolve on the concrete ties. During

this period suitable gage means are preferably connected between the rails in order to preserve the alinement and gage. At this time the rails may settle, but only to a very small extent, not sufficient to disturb the original setting; this for the reason that the legs 6 and 7 on any tendency of the rail to sink into a tie will force a wedged-shaped mass of the green concrete up into the space between the legs and this will not only check downward movement of the rail, but the legs will prevent any canting of the rail.

From the foregoing, it will be apparent that the rail is held more securely than heretofore without the use of any external fastenings.

It is obvious that various changes and modifications may be made in the details of construction and design of the above specifically described embodiment of this invention without departing from the spirit thereof, such changes and modifications being restricted only by the scope of the following claims.

25. What is claimed is:

1. A railroad comprising concrete ties and rails having webs with divergent legs extending downwardly from the lower edges of the webs and enclosing substantially wedge shaped spaces, said legs being imbedded in the concrete with a wedge shaped mass of concrete between the legs and with portions of concrete on opposite sides of said legs.

2. A railroad comprising a rail having a web and legs projecting downwardly and outwardly from the web in substantially diagonal directions and diverging downwardly whereby to enclose a wedge shaped space, said web having a seat at its base between the two legs, and concrete ties moulded about the lower portion of said web and said legs and having a wedge shaped mass between the legs with portions of the concrete on the exterior surface of said legs, said shoulder adapted to seat upon the concrete ties at substantially the upper surface thereof.

STEPHEN NICAS.
